CLAIM

The ornamental design for a fender for motor vehicle as shown and described.

DESCRIPTION

FIG. 1 is a perspective view of a fender for motor vehicle showing my new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines in the drawings illustrate portions of the fender for motor vehicle that form no part of the claimed design.

The color black indicates color contrast.

1 Claim, 7 Drawing Sheets
